CLAIM

The ornamental design for a mirror, as shown and described.

DESCRIPTION

FIG. 1 is a top, front, and right perspective view of a mirror, showing my new design;

FIG. 2 is a bottom, rear, and left perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is an enlarged detail view of area 9 of FIG. 2.

The evenly broken lines show the features of the mirror that form no part of the claimed design. The unevenly broken lines illustrate the boundary of the enlarged view that form no part of the claimed design.

1 Claim, 9 Drawing Sheets
